UNITED STATES PATENT OFFICE.

MEYER W. SCHLOSS, OF NEW YORK, N. Y.

DESIGN FOR BRAID.

SPECIFICATION forming part of Design No. 28,881, dated June 14, 1898.

Application filed May 11, 1898. Serial No. 680,417. Term of patent 3½ years.

To all whom it may concern:

Be it known that I, MEYER W. SCHLOSS, a citizen of the United States, residing at the city of New York, (in the borough of Brooklyn,) State of New York, have invented and produced a new and original Design for a Braid, of which the following is a specification, reference being had to the accompanying drawing, forming part thereof.

10 The figure shows a face view of the braid illustrating my new design.

The leading or material feature of my design consists of a series of narrow stripes *a* of two contrasting colors, the stripes of one 15 color alternating with those of the other, and a wider stripe or band *b* of a color which contrasts with the other two. This wider stripe occupies one edge, while the series of alter-

nately-arranged narrow stripes extends from the wide stripe to the opposite edge. The 20 wide stripe *b* is interspersed with regularly-disposed bright spots, and the same bright spots are interspersed upon the narrower alternating stripes, but are not so clearly visible on account of the contrast being less pronounced.

What I claim as new, and desire to secure by Letters Patent, is—

The design for a braid as herein shown and described.

In witness whereof I subscribe my signature in presence of two witnesses.

30 MEYER W. SCHLOSS.

Witnesses:

FRANK S. OBER,

JAMES OPPENHEIM.
